UNITED STATES PATENT OFFICE.

ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST-PULLING MACHINE.

1,291,757.

Specification of Letters Patent.

Patented Jan. 21, 1919.

Application filed August 18, 1915. Serial No. 46,205.

To all whom it may concern:

Be it known that I, ELI BROTHERS, a citizen of the United States, residing at Lynn, in the county of Essex and State of Massachusetts, have invented certain Improvements in Last-Pulling Machines, of which the following description, in connection with the accompanying drawings, is a specification, like reference characters on the drawings indicating like parts in the several figures.

This invention relates to last pulling machines or devices, for separating shoes and lasts. After a shoe has been lasted, the upper is held in tight conformity to the last and it is a difficult operation to separate the shoe and last without injury to the shoe. This operation, when accomplished by hand, requires considerable skill and strength, as well as time. Furthermore, the separation of the parts subjects the shoe upper to severe strain and unless care is exercised there is danger that the shoe may be ruined.

The present invention provides a device of simple construction arranged to effect the separation of the shoe and last so as to reduce the strains upon the shoe to a minimum.

One feature of this invention consists in a novel construction providing means for engaging and holding a shoe during the removal of its last, said means being arranged for hand operation. Such a construction permits the operator instantly to release the shoe to save it from being strained or torn, should the last stick for any reason or should the upper prove defective and start to give or break out.

Another feature of the invention consists in a construction which will permit the operator to position the parts so that separation is effected with minimum strain to the shoe. In the embodiment of the device selected for illustration, this end is attained by a construction of shoe holding means which permits the operator to move the shoe relative to the line of last pulling force.

A further feature of the invention consists in a device for removing lasts from shoes in the manner heretofore described which is of simple construction and in which the power is furnished by the operator. Such a device may be used to advantage in small factories where the cost or lack of

power facilities makes a power machine undesirable.

55

Another feature of the invention consists in the combination of last holding means and shoe engaging means operated by hand to engage and hold a shoe mounted on a last for the removal of its last, with the last holding means constructed and arranged for actuation by the operator to pull the last from the shoe while the operator is holding the shoe by hand. Additionally, the holding of the shoe through the hands of the operator permits the shoe to be moved during the pulling of the last to facilitate the separation of the last and shoe.

65

A further feature consists in means to engage and hold a last in combination with means arranged to be held by hand in holding engagement with a shoe to permit the removal of the last, the last holding means being movable in a direction to remove the last from the held shoe.

75

A further and related feature consists in the means for engaging and holding a last with its shoe at an angle to the horizontal and preferably with the heel of the shoe and last inclining upwardly. This last position facilitates the downward and rearward movement of the last and materially reduces the strain upon the shoe upper during the initial stages of last removal.

80

These and other features of advantage including the specific construction of the shoe engaging and holding means, will be more fully apparent from the detailed description following and from the illustrative embodiment of the invention shown in the accompanying drawings, in which—

85

Figure 1 is a view in elevation of a preferred embodiment of my device, illustrating a shoe and last in operative position relative to the last holding means and the shoe gripping means and in the position they occupy at the initiation of the last pulling operation; and

95

Fig. 2 is a plan view of the heel end of the manually held shoe showing the engagement of the shoe gripping means therewith.

100

A suitable standard 2, preferably hollow, has its upper end provided with a forwardly projecting arm 4 having an elongated slot 6 formed therein adjacent its front terminal. At the rear side of its upper end the stand-

105

ard carries an upwardly extending bracket 8 designed to receive the shoe engaging means.

The means for engaging and supporting the last is housed in part within the standard and comprises a rod 10 whose lower end is pivotally attached to a treadle 12, the rear end of which is pivoted to the base of the standard. The upper end of the rod 10 is secured to a sliding plunger 14 of relatively greater diameter guided for substantially vertical movement within the standard 2. A coiled spring 16 is interposed between the lower end of the plunger and an abutment 18 within the standard serving also as a guide for the rod 10. The coiled spring normally operates against the plunger and rod to move these parts upwardly into the position shown in Fig. 1 of the drawings. A stop 20 secured to the rod 10 below the abutment 18 serves to limit the upward movement of the plunger and rod so as to position the plunger with its attached last holding parts for co-operation 25 with the shoe engaging and gripping means.

A last holding means is provided in the form of an angular jack 22 pivoted to the upper end of the plunger 14 at the apex of its angle, as at 24, and having its upper end 30 provided with a last pin 26 for insertion into the thimble of the last to grip and hold the last. The lower end of the jack is provided with a laterally extending pin 28 (Fig. 1) extending in and guided by the slot 6 in the forward arm of the standard 2. From the positions of the parts as seen in Fig. 1 of the drawings, it will be evident that the last holding means is normally positioned to receive and hold the last and shoe inclined at an angle to the horizontal and with the heel of the last and shoe inclined upwardly. In this position of the parts, the shoe will be supported in an inverted position with its heel portion toward 45 the rear of the standard.

The bracket 8 carries at its upper end the shoe engaging and gripping means. One form which these means may take comprises an arm 30 pivotally attached to the bracket 50 8 and having its upper end formed as a V-shaped plate 32 arranged to engage the heel portion of the shoe counter at opposite sides of the longitudinal median line of the shoe. Preferably, also, means are provided for engaging the forepart of the shoe. Such a means may take the form of a curved arm 34 branching from the heel gripping arm 30 and arranged to engage the forward portion of the shoe sole with its foot 36. While 60 such a means is desirable in that it tends to prevent the bending of the shoe sole and the consequent cracking of the finish, it will be understood that the heel gripping plate may be used alone. This plate, as shown, 65 is arranged to be moved to engage and grip

the shoe but it will be obvious that the arrangement may be reversed within the scope of the invention.

In the operation of the device described, the last with its shoe is first mounted upon 70 the last pin 26 of the jack and cramped into firm holding engagement therewith. The operator then moves the shoe gripping arm 30 toward the shoe and manually holds the heel engaging plate 32 against the heel portion of the shoe counter, this movement bringing the foot 36 against the forward portion of the shoe sole. The operator then depresses the treadle 12, firmly holding the plate 32 against the shoe and, at the same 80 time, pressing downwardly upon the treadle. Both hands of the operator may be used, one to hold the heel plate and the other to engage the forepart of the shoe as the shoe is swung about its transverse axis. The forepart is moved upwardly and the rear part downwardly during the downward movement of the plunger 14 as the operator pulls against the shoe during the descent of the plunger to "ease" the last extracting opera- 85 tion and minimize the strain on the shoe during the pulling of the last. In the illustrated device, the shoe holding means will be permitted by the operator slightly to swing backward on its pivot but without releasing the shoe so that the position of the shoe may be accommodated to the line of last movement and the extracting operation facilitated by "easing" the shoe relatively to the last. The sole will be flexed somewhat 100 during the extraction of the last but not to an injurious degree. The movement of the shoe holding arm is closely analogous to the movement of a person's hand when he pulls his foot from the shoe by movement of the leg while the hand grasps the counter of the shoe and "eases" the shoe from the foot. In the illustrated device the last will not be pulled entirely from the shoe but to the point where the heel of the last has sub- 105 stantially cleared the shoe counter when the last is extracted to such a substantial degree that the shoe may readily be stripped from the last by hand after the arm 30 is swung backwardly and away from the shoe. 110

When pressure is applied to the treadle 12 the rod 10 and plunger 14 will be pulled downwardly against the tension of the spring 16. The jack 22 will be in firm holding engagement with the last and will pull 120 the last from the shoe along a curved line having one component substantially perpendicular to the plane of the shoe bottom and with a second and lengthwise component of movement in the direction of the heel of 125 the shoe as permitted by the different relative positions of the shoe and last. Or, it may be said to have a movement perpendicularly to the plane of the shoe bottom with a component of movement lengthwise heel- 130

ward of the shoe. This lengthwise component of movement will increase substantially when the bottom of the last heel clears the edge of the shoe counter. The pin 28 at 5 the forward end of the jack will slide forwardly in the slot 6, the long arm of the jack swinging downwardly as the jack is pulled downwardly by the plunger. The pin 28 will move toward the forward end of 10 the slot 6 as the last is pulled downwardly to a point where it is substantially removed from the shoe. When this point has been reached the operator releases the gripping arm 30, removes the shoe and unspindles the 15 last from the jack. If, at any time during the last pulling operation, the shoe should start to break out, either through the sticking of the last, or for any other reason, the operator may immediately release the shoe 20 gripping plate 32 whereupon the shoe will be pulled downwardly with the last and will be saved from injury.

Having thus described my invention, what I claim as new and desire to secure by Letters Patent of the United States is:—

1. A machine of the class described having, in combination, means for manually engaging and holding a shoe for the removal of a last, and last engaging and holding means, with means for operating said last holding means to move the last from the shoe along a curved line having one component substantially perpendicular to the plane of the shoe bottom and having a second component lengthwise heelward of the shoe.

2. A machine of the class described having, in combination, means for manually engaging and holding a shoe for the removal of a last, said shoe being manually releasable, last engaging and holding means, with means for operating said last holding means to move the last from the shoe along a curved line having one component substantially perpendicular to the plane of the bottom of the manually held shoe and having a second component lengthwise heelward of the shoe.

3. A machine of the class described having, in combination, manually operated means for engaging and holding a shoe for the removal of a last including a plate arranged to be manually held in engagement with the counter portion of a shoe upper at 55 opposite sides of the longitudinal median line of the shoe, and last engaging and holding means with operating connections arranged to actuate the last holding means to remove the last from the shoe in a direction 60 having one component substantially perpendicular to the plane of the shoe bottom and a second component of movement lengthwise of the shoe.

4. A machine of the class described having, in combination, means to engage and

hold a last, means arranged to be held by hand in holding engagement with a shoe mounted on a last, and means arranged to be actuated by the operator while holding the shoe by hand, for moving the last holding means to pull the last from its shoe. 70

5. A machine of the class described having, in combination, means to engage and hold a last, means arranged to be held by hand in holding engagement with a shoe 75 mounted on a last, and means arranged to be actuated by the operator while holding the shoe by hand, for moving the last holding means to pull the last from its shoe, said shoe holding means being constructed 80 and arranged to permit the operator to move the shoe during the pulling of the last to facilitate its removal.

6. A machine of the class described having, in combination, means for manually engaging and holding a shoe for the removal of a last including means to engage the counter of the shoe at opposite sides of its longitudinal median line, and means to engage the forepart of the shoe, and last engaging and holding means, with operating connections therefor adapted to actuate the last holding means to move the last from the shoe along a curved line having one component substantially perpendicular to the plane 90 of the bottom of the manually held shoe and having a second component lengthwise heelward of the shoe. 95

7. A machine of the class described having, in combination, means to engage and hold a last, means arranged to be moved and held by hand to engage opposite sides of the counter portion of a shoe to hold the shoe for the removal of its last, and means controlled by the operator for moving the last holding means to pull the last from the hand-held shoe. 100

8. A machine of the class described having, in combination, means arranged to engage and support a last with its shoe thereon, means arranged to be held by hand in holding engagement with a shoe to permit the removal of the last, and means arranged to operate said last holding means to remove the last from the held shoe. 110

9. A machine of the class described having, in combination, means arranged to engage and support a last with its shoe thereon and with the shoe and last inclined to the horizontal, means arranged to be held by hand in holding engagement with a shoe to permit the removal of the last, and means to operate the last holding means in a direction to remove the last from the held shoe. 120

10. A machine of the class described having, in combination, means arranged to engage and support a last with a shoe thereon, shoe engaging means arranged to be manually moved and maintained in engagement 130

- with the shoe to hold the shoe for the removal of the last, and means arranged to operate the last engaging means to move the last out of the shoe in a direction having one component substantially perpendicular to the plane of the shoe bottom and a second component of movement lengthwise of the shoe.
11. A machine of the class described having, in combination, means to engage and hold a last with its shoe thereon, means arranged to be held by hand in holding engagement with a shoe to permit the removal of the last, with means operable to move the last holding means in the direction to remove the last from the held shoe, said shoe holding means being movable under manual control to ease the shoe off the last as the last is pulled from the shoe.
12. A machine of the class described having, in combination, means to engage and hold a last with its shoe thereon, means arranged to be held by hand in holding engagement with a shoe to permit the removal of the last, and foot operated means for moving the last holding means in the direction to remove the last from the held shoe, said shoe holding means being manually movable to vary the position of the shoe relatively to the last removing means to ease the shoe off the last as the last is pulled from the shoe.
13. A machine of the class described having, in combination, means arranged to engage and hold a last with its shoe thereon, shoe engaging means arranged to be manually moved and held in engagement with the shoe to hold the shoe for the removal of the last, and means operable to actuate the last holding means to move the last from the shoe along a curved line having one component substantially perpendicular to the plane of the bottom of the manually held shoe and having a second component lengthwise heelward thereof, said shoe engaging means being manually adjustable to move the shoe about its transverse axis to vary the position of the shoe relatively to the last moving means to ease the shoe off the last as the last is pulled from the shoe.
14. A machine of the class described having, in combination, means arranged to engage and hold a last with its shoe thereon, shoe engaging means arranged to be manually moved and held in engagement with the shoe to hold the shoe for removal of the last, and foot-operated means operable to actuate the last holding means to move the last from the shoe in a direction having one component substantially perpendicular to the plane of the bottom of the manually held shoe with a component of movement lengthwise heelward thereof, said shoe engaging means being manually adjustable to move the shoe about its transverse axis to

vary the position of the shoe relatively to the last moving means to ease the shoe off the last as the last is pulled from the shoe.

15. A machine of the class described having, in combination, means to engage and hold a last with its shoe thereon, means for manually engaging and holding the shoe for the removal of the last including a shoe gripping member mounted to be manually swung about an axis transversely of the shoe, and means to move the last holding means to move the last from the shoe along a curved line having one component substantially perpendicular to the plane of the bottom of the held shoe and having a second component lengthwise heelward of the shoe.

16. A machine of the class described having, in combination, means to engage and hold a last with its shoe thereon, means for manually engaging and holding the shoe for the removal of the last including a shoe gripping member mounted to be manually swung about an axis transversely of the shoe, and foot operated means to move the last holding means to move the last from the shoe along a curved line having one component substantially perpendicular to the plane of the bottom of the held shoe and having a second component lengthwise heelward of the shoe.

17. A machine of the class described having, in combination, means arranged to engage and hold a last including a spindle to engage and grip the last, means for manually engaging and holding the shoe for the removal of the last, and means for moving said spindle to pull said last from the shoe in a direction having one component substantially perpendicular to the plane of the bottom of the held shoe with a component of movement lengthwise heelward of the shoe.

18. A machine of the class described having, in combination, means arranged to engage and hold a last including a swinging jack having a spindle to engage and grip the last, means for manually engaging and holding the shoe for the removal of the last, and operating means in connection with the jack and arranged to swing the jack to move the last from the shoe along a curved line having one component substantially perpendicular to the plane of the bottom of the held shoe and having a second component lengthwise heelward of the shoe.

19. A machine of the class described having, in combination, means arranged to engage and hold a last including a swinging jack having a spindle to engage and grip the last with means normally positioning said jack and spindle at an angle to the horizontal, means for manually engaging and holding the shoe for the removal of the last, and operating connections to said jack ar-

ranged to swing the jack to move the last from the shoe along a curved line having one component substantially perpendicular to the plane of the bottom of the held shoe and 5 having a second component lengthwise heelward of the shoe.

20. A machine of the class described having, in combination, means arranged to engage and support a last with its shoe thereon 10 including a jack swinging on an axis transversely of the last and having a spindle to engage and grip the last, a shoe engaging member mounted to swing on an axis transversely of the shoe and last and arranged to 15 be manually held in engagement with the shoe to hold the shoe for the removal of its last, means normally positioning the jack for gripping coöperation between the shoe and its engaging member, and foot operated connections to said jack for swinging the jack 20 in an arc giving the last a movement relatively to the shoe along a curved line having one component substantially perpendicular to the plane of the bottom of the held shoe 25 and having a second component lengthwise heelward of the shoe to remove the last from the shoe.

21. A machine of the class described, comprising means adapted to be manually moved 30 and held against a shoe to hold a shoe for the removal of its last, last engaging and holding means, and operating connections to the last holding means arranged to be moved by the operator to pull the last from the shoe 35 along a curved line having one component substantially perpendicular to the plane of the bottom of the held shoe and having a second component lengthwise heelward of the shoe.

40 22. A machine of the class described, comprising means adapted to be manually moved and held against a shoe to hold a shoe for the removal of its last, means to engage and hold the last, and foot-power operated connections to the last holding means constructed and arranged to pull the last from 45

the held shoe along a curved line having one component substantially perpendicular to the plane of the shoe bottom and having a second component lengthwise heelward of 50 the shoe, the manually held shoe holding means being arranged for movement at the will of the operator during the pulling of the last to vary the position of the shoe relatively to the last pulling means to ease the 55 shoe off the last.

23. A machine of the class described having, in combination, shoe engaging and holding means, and last engaging and pulling means having a determinate line of last pull- 60 ing movement, the shoe engaging means being constructed and arranged to be moved and held by hand in holding engagement with the shoe and being mounted for movement under the control of the operator to 65 permit the operator to change the position of the shoe relative to the line of last pulling force during the operation of the last pulling means.

24. A machine of the class described hav- 70 ing, in combination, means to engage and hold a last, means arranged to be moved and held by hand to engage and hold a shoe for the removal of its last, and foot controlled means for moving the last holding means to 75 pull the last from a held shoe.

25. A machine of the class described having, in combination, means to engage and hold a last, shoe holding means arranged to be moved and held by hand in gripping en- 80 gagement with a shoe to hold the shoe for the removal of its last, and foot controlled means for determinately moving the last holding means to pull the last from the held shoe, said shoe holding means being con- 85 structed and arranged to permit the operator to move the shoe relatively to the last during the last pulling operation to facilitate the separation of the last and shoe.

In testimony whereof I have signed my 90 name to this specification.

ELI BROTHERS.
